UNITED STATES PATENT OFFICE.

HUGO W. WEIMER, OF MILWAUKEE, WISCONSIN, ASSIGNOR TO WORTHINGTON
PUMP AND MACHINERY CORPORATION, OF NEW YORK, N. Y., A CORPORATION
OF VIRGINIA.

TUBE-MILL.

1,291,311.

Specification of Letters Patent. Patented Jan. 14, 1919.

Application filed March 25, 1918. Serial No. 224,407.

To all whom it may concern:

Be it known that I, HUGO W. WEIMER, a citizen of the United States, residing at Milwaukee, county of Milwaukee and State of Wisconsin, have invented certain new and useful Improvements in Tube-Mills, fully described and represented in the following specification and the accompanying drawings, forming a part of the same.

10 This invention relates particularly to that well known class of machines for grinding or crushing ore and other materials, commonly known as tube mills or ball mills, the especial object being to provide an improved discharge diaphragm or screen construction for such mills.

The discharge diaphragms or screens used on such mills are large and heavy, and it has been found difficult to mount them satisfactorily so that they are held rigidly in position and against movement around the mill in the direction of its rotation, while at the same time providing for a quick and convenient removal and replacement of the 25 diaphragm and screen when necessary. The present invention provides a very simple, cheap and efficient construction and mounting of the diaphragm, in which the diaphragm is divided into sections hinged at 30 their outer periphery in such manner as to avoid rotation in the mill head, and with the sections secured at the center, so that the sections may readily be connected to the head at their periphery and then swung 35 downward and secured at the center by a single holding means and any section may readily be removed and replaced by releasing the holding means without moving the other sections.

40 For a full understanding of the invention, a detailed description of a construction embodying the invention in its preferred form, as applied to a tube mill of a common type, will now be given in connection with the 45 accompanying drawings forming a part of this specification, and the features forming the invention then specifically pointed out in the claims.

In the drawings:—

50 Figure 1 is a central section of one end of the rotating barrel or tube of a tube mill embodying the invention.

Figs. 2 and 3 are cross sections on the lines 2—2 and 3—3 of Fig. 1.

55 Referring to the drawings, A is the ro-

tating barrel or tube, shown as driven by gear B and having the usual head C, hollow discharge trunnion D mounted in bearing E, and discharge funnel F. The head C and trunnion D are shown as formed of an outer sheel and inner lining of suitable material, and the trunnion is shown as having the helical discharge wings 10 usual in this class of mills.

60 Referring now to the parts of the apparatus especially embodying the invention, the discharge diaphragm G between the barrel or tube A and the discharge, is divided into sections of suitable number, according to the size of the mill, and preferably of 65 sector-like form, six such sections being shown in the present case. Each of these sections has at its periphery a projecting lug 11 adapted to be inserted in a recess or socket 12 in the liner or head C, so that the 70 parts 11, 12 form a hinge such that the section may readily be mounted in place by inserting the lug 11 into the recess 12 and swinging the section downward into a vertical plane and the section is then held against 75 sidewise movement by the hinge, and may be removed readily after swinging it upward from the vertical plane. The inner ends of the diaphragm sections when in 80 place form an opening shown as receiving a hub on washer 13 mounted on the discharge hub 14 extending through the discharge and bored to receive bolt 15 by which the inner ends of the sections are locked in 85 place between washer 13 and another washer 16 on the inner side of the diaphragm. The bolt 15 is shown as secured by nuts 1 at the outer end of the discharge hub, so as to be readily accessible through the discharge funnel F. Between the diaphragm 90 G and the head are the usual lifters or partition plates H, four being shown, which are held in position at their outer ends between lugs 2 on the liner of head C and at their inner ends in notches 3 in hub 14, 95 so as to rotate with the barrel and diaphragm.

100 The assembling and disassembling of the diaphragm will be understood from the drawings with a brief description.

105 The sections are mounted successively by inserting the lugs 11 into the sockets 12 and swinging the sections together at the center, the sections then preferably being permanently fastened at their periphery by 110

wooden wedges driven into the sockets. The washer 16 is then positioned against the inner edges of the sections and center bolt 15 drawn up and secured by nuts 1, so as to hold the edges of the sections rigidly in place. When any diaphragm section is to be removed, the nuts 1 are withdrawn, the washer 16 and bolt 15 slipped back into the barrel sufficiently to release the inner end of the section, the wedges in socket 12 are removed, and the section swung upward for release.

While the invention has been described as applied to that special type of crushing or grinding apparatus known as tube mills or ball mills, it will be understood that the invention is not thus limited, but is generally applicable in similar apparatus employing a diaphragm or screen on either the inlet or discharge. It will be understood also that the invention is not limited to the specific construction shown, but that modifications may be made within the invention as defined by the claims.

25 25. What is claimed is:

1. In a tube mill or the like, a diaphragm divided into sections, in combination with means for hinging the sections to the mill at their outer periphery and securing the 30 sections at the center.
2. In a tube mill or the like, a diaphragm divided into sections, in combination with means for hinging the sections to the mill at their outer periphery, and a single clamping means for securing all the inner edges 35 of the sections at the center.
3. In a tube mill or the like, the combination with a transverse head or wall having recesses forming one member of a hinge, of 40 a diaphragm divided into sections, each of said sections having lugs entering said re-

cesses to form the other members of the hinge, said recesses and lugs being formed to hold the diaphragm against withdrawal when in working position and to permit 45 the sections to be inserted and removed when swung out of working position, and a single clamping means for securing the inner edges of the sections in working position.

4. In a tube mill or the like, the combination with a transverse head or wall having recesses forming one member of a hinge, of a diaphragm divided into sections, each of said sections having lugs entering said recesses to form the other members of the hinge, said recesses and lugs being formed to hold the diaphragm against withdrawal when in working position and to permit the sections to be inserted and removed when swung out of working position, a fixed hub 60 within the inner edges of the diaphragm sections, a bolt extending through the hub, and a clamping washer on said bolt for holding the inner edges of the diaphragm sections in working position.

5. In a tube mill or the like, the combination with a transverse head or wall, of a diaphragm divided into sections, means for hinging the sections to the head so arranged as to hold the diaphragm sections against 70 withdrawal when in working position and to release the sections when swung out of working position, a fixed hub within the inner edges of the diaphragm sections, a bolt extending through the hub, and a clamping 75 washer on said bolt for holding the inner edges of the diaphragm sections in working position.

In testimony whereof, I have hereunto set my hand.

HUGO W. WEIMER.
